UNITED STATES PATENT OFFICE.

ALLIE WILLMAN, OF NEW HAVEN, CONNECTICUT, ASSIGNOR OF ONE-HALF TO PETER J. TORELLO, OF NEW HAVEN, CONNECTICUT.

INTAKE LOCK.

Application filed May 8, 1922. Serial No. 559,315.

To all whom it may concern:

Be it known that I, ALLIE WILLMAN, a citizen of the United States, residing at New Haven, in the county of New Haven and State of Connecticut, have invented certain new and useful Improvements in Intake Locks, of which the following is a specification, reference being had therein to the accompanying drawings.

- 10 This invention relates to an intake lock and is designed to shut off the supply of explosive mixture to the manifold of a motor vehicle so as to prevent surreptitious use thereof.
- 15 It is the principal object of the invention to provide means to effectually prevent the operation of the motor vehicle except by one who is familiar with the lock and knows both its location and operation, and
- 20 also has the necessary means to manipulate the same.

One of the objects of my invention is to provide a locking device whose location is practically unknown, as well as its presence

25 and the means by which the motor vehicle is locked against use cannot be readily ascertained.

Among other aims and objects of the invention may be recited the provision of a 30 device of the character mentioned, with a view to compactness, in which the number of parts are few, the construction simple, cost of production small and efficiency and operation high.

35 The improvements in the details and arrangement of parts will be apparent from an inspection of the accompanying drawings, in connection with the description hereinafter contained, and wherein an embodiment of the invention is disclosed for the purpose of imparting an understanding of the same.

In the drawings like characters of reference designate corresponding parts; and

40 Figure 1 is a side elevation of my improved intake lock, partly in section, and shown in its applied position in relation to the carburetor and manifold respectively;

Figure 2 is a plan view thereof;

45 Figure 3 is a plan view of the lower section of the body member with the closure plate shown in connection therewith; and

50 Figure 4 is a cross sectional view of the improved intake lock and the adjacent parts, taken generally upon line 4—4 of Figure 2.

In the practice of my invention, I provide a body member which is constructed of a lower section 10 and an upper section 11, which in their assembled form are brazed or soldered together so as to form a 60 unitary structure.

The lower section 10 has a recess 12 in its inner face and both sections are provided with openings 13 and 14, which are of substantially the same size, and opposite each other.

Fixed in the lug 15 on the upper section 11 by the dowel pin 16, or other means, is a key cylinder 17, which is of a usual form and structure, and within which is projected 70 the bit of a key 18 by which it is rotated, as well as the spindle 19 having a pinion 20 on the lower end thereof.

Within the recess 12 is a closure plate 21 having a rack 22 upon one edge thereof, the 75 teeth of which mesh into those of the pinion 20, and by the rotation of which a reciprocating movement is imparted to the closure plate. In Figure 3 this closure plate is shown in its retracted position, but in its 80 forward position it entirely covers the openings 13 and 14.

My improved intake lock is preferably mounted between the carburetor 23' of the motor vehicle and the manifold, being so secured by the bolts 23 which pass through openings in said body member and are locked against movement by studs 26.

The ports 27 and 28 in the carburetor and manifold respectively register with the openings 13 and 14 so that the explosive mixture passes directly through the intake lock from the carburetor to the manifold when the closure plate 21 is in its open or retracted position but is shut off from passage to the 95 manifold when said closure plate is in its closed or forward position.

As this closure plate is actuated by the key it is a simple matter for the motor vehicle operator to prevent operation thereof by 100 merely closing the port through which the explosive mixture passes to the cylinders by moving the closure plate 21 to its closed or forward position through manipulation of the key. As shown, the lock is operated by 105 a key but other means may be provided for the same purpose.

Minor changes and alterations may be made within my invention, aside from those herein suggested, and I would therefore have 110

it understood that I do not limit myself to the exact construction herein shown and described, but claim all that falls fairly within the spirit and scope of the appended claims.

5 Having described my invention, what I claim as new and desire to secure by Letters Patent, is:

1. In an intake lock for internal combustion engines, a pair of superimposed perforated registering sections one of which has a continuous recess in its inner face, a slideable closure plate for the perforations having a rack on one side edge thereof slideable in the recess, a pinion in the recess in mesh with the rack, the inner face of the other section engaging the plate and pinion to hold both of the latter in the recess, said sections being brazed together, a hollow lug extending upwardly from said other section, a lock barrel in the lug having a key-actuated spindle connected to the pinion, and means to secure the sections to the manifold pipe and carbureter including bolts extending through the sections, and connected to the manifold pipe and carbureter and studs screwed through the sections and impinged against the bolts so as to allow of removal of the nuts of the bolts and disconnection of the manifold pipe without disturbing the remaining parts.

2. In an intake lock for internal combustion engines, a pair of superimposed perforated registering sections one of which has a continuous recess in its inner face, a closure plate for the perforations, having a rack on one side edge thereof, slideable in the recess, a pinion in the recess in mesh with the rack, the inner face of the other section en-

gaging the plate and pinion to hold both of the latter in the recess, said sections being 40 brazed together, a hollow lug extending upwardly from said other section, a lock barrel in the lug having a key actuated spindle connected to the pinion, and means to secure the sections to the manifold pipe and carbureter. 45

3. In an intake lock for internal combustion engines, a pair of relatively thin superimposed perforated registering sections, a relatively thin closure plate for the perforations disposed between the sections and having a rack on one side edge, a pinion between the sections meshed with the rack, the plate and pinion being each completely housed by the sections, a spindle connected at one end to the pinion and having its opposite end formed to receive a key, a lock barrel enclosing the spindle and carried by one section, and means to secure the sections to and between the inlet manifold and carbureter. 55

4. In an intake lock for internal combustion engines, a casing interposed between the carbureter and intake manifold and having an opening communicating with each, lock-controlled means for controlling the opening carried by the casing, bolts having nuts, 60 extending through parts of the casing, the carbureter and intake manifold for securing the casing in its said position, and studs carried by the casing and impinged against the bolts whereby the manifold pipe may be 65 disconnected from the casing by mere removal of the nuts and without disturbing the remaining parts.

In testimony whereof, I have hereunto affixed my signature.

ALLIE WILLMAN.
